UNITED STATES PATENT OFFICE

RAY F. GORDON AND JAMES S. GWALTNEY, OF SUFFOLK, VIRGINIA

AIR CLEANER

Application filed December 18, 1929. Serial No. 413,892.

This invention relates to attachments for internal combustion engines and has for an object the provision of a device which will clean the air before it enters the engine carbureter, and at the same time will prevent dangerous gas fumes from accumulating in the bottom of the automobile. In addition it will relieve the engine crank case of undue pressure, and will utilize heated 10 crank case vapor to improve the fuel mixture and increase the fuel mileage.

As is well known, when an engine is operated for a protracted period, oil and gasoline vapors accumulate in the engine crank 15 case, and these vapors sometimes accumulate in the automobile hood and pass into the body so that the occupants are subjected to the inconvenience and danger of these fumes.

In addition, these vapors, by their accumulation in the engine crank case cause an accumulation of pressure and consequent leakage of oil where gaskets are not in perfect condition.

The present invention overcomes the above 25 and many other disadvantages, and provides in addition, many advantageous features which increase the safety and efficiency of an engine as well as reduce the cost of operation, and therefore materially add to the 30 comfort of the occupants of an automobile.

With the above and other objects in view, the invention further includes the following novel features and details of construction, to be hereinafter more fully described, illustrated in the accompanying drawings and 35 pointed out in the appended claim.

In the drawings:—

Figure 1 is a fragmentary side elevation showing a portion of an automobile with its 40 engine and the invention applied.

Figure 2 is a vertical sectional view through the suction valve.

Figures 3 and 4 are sections taken substantially on the line 3—3 and 4—4 respectively of Figure 2.

Figure 5 is an enlarged section through the air cleaner.

Figures 6 and 7 are sectional views taken respectively on the lines 6—6 and 7—7 of Figure 5.

Referring to the drawings in detail where-in like characters of reference denote corresponding parts, the reference character 10 indicates the dash of an automobile, 11 a portion of an internal combustion engine, 12 the engine carbureter which has connection with the usual intake manifold for supplying fuel to the engine cylinders in the ordinary manner. The engine shown is of the poppet valve type, the valve cover plates 13 being indicated at 13. These plates form the outer wall of a chamber through which the valve stems pass in the ordinary manner, and this chamber is in communication with the crank case 14 of the engine as is well known. All of the foregoing is of the usual or any preferred type of poppet valve engine structure.

The reference character 15 indicates an air cleaner and one end of this air cleaner 70 is in communication with the air intake of the carbureter 12 by means of a pipe 16. The opposite end of the air cleaner 15 has extending therefrom a nipple or elbow 17 through which air enters the cleaner as 75 shown in Figure 5 of the drawings.

The cleaner may be of any suitable construction, the one shown being barrel-shaped and provided with a plurality of curved baffles 18, so that air entering the cleaner through the nipple 17 must pass around these baffles in order to escape through the pipe 16 to the carbureter. During the passage of the air through the 80 cleaner, dust, dirt, and other extraneous matter will adhere to the baffles and thus be prevented from entering the carbureter, so that air passing into the carbureter for mixture with the liquid fuel will be free of all 85 90

matter which might prove injurious to the engine.

Ordinarily, the air intake end of an air cleaner is directly open to the atmosphere.

- 5 In the present invention, air enters the cleaner through a pipe 19 which is in communication with the interior of the body of an automobile through a register 20 having a screen 21 to prevent the entrance of 10 large particles of dirt. The pipe 19 communicates with the register through a valve casing 22 which encloses a suction operated valve 23. This valve is of the mushroom type and is normally engaged with the seat 15 24 by means of a spring 25 and is opened by suction from the engine. The valve casing 22 is closed at opposite ends by means of threaded plugs 26 and the stem 27 of the valve operates within a guide 28 having 20 openings 29 for the passage of air.

Normally, the valve 23 is closed. Suction provided by the operation of the engine, will open the valve and draw air into the carburetor through the register 20, the valve 25 casing 22, the pipe 19 and the air cleaner 15, so that the air will be cleaned before it enters the carburetor. In the event of back pressure caused by back firing through the carburetor, the valve 23 will be immediately 30 seated so as to prevent this back pressure air entering the body of the automobile. A pressure relief valve 30 is provided in the bottom of the air cleaner 15. This valve is normally spring closed and back pressure 35 through the cleaner will open this valve 30 so as to permit of the escape of this pressure.

By drawing the air from the interior of the automobile, danger of accumulation of 40 noxious fumes within the automobile will be avoided, any fumes passing from beneath the hood of the automobile into the body will be quickly drawn outward through the register 20.

45 The air cleaner 15 is also in communication with the crank case 14 of the engine through the valve chamber mentioned. For this purpose, a pipe 31 which is attached to the cleaner and to the valve plate 13 is provided. Pressure accumulating within the crank case will cause the heated oil and gasoline vapors to enter the air cleaner through the pipe 31 and pass into the carburetor through the pipe 16.

55 These otherwise wasted vapors will be added to the fuel mixture and will increase the efficiency of the mixture and the operation of the engine, as well as increase the fuel mileage. In addition, this manner of 60 disposing of the crank case vapor will prevent undue accumulation of this vapor within the crank case and its escape into the hood, so that passage of the vapor into the interior of the automobile will be prevented 65 or materially reduced.

When the engine is running with the throttle retarded or in idling position, the suction is through the pipe 31 from the crank case only, the spring 25 being of sufficient strength to maintain the valve 23 seated. This acts to clear the crank case of the engine of all gases and fumes, which might otherwise enter the automobile. When the throttle is opened partially, the suction is increased, so that the valve 23 will be opened and suction will be through the pipe 19 in addition to the pipe 31, so that there can be no collection of gases within the body of the automobile. One group of the baffles 18 is adapted to direct the incoming air from the pipe 17 downwardly toward the bottom of the casing 15, while the other group of baffles 18 is adapted to direct said air toward the outlet which is in communication with the pipe 16 leading to the carburetor. The air and vapors entering the casing from the pipe 31 are directed downwardly toward the bottom of the casing by the uppermost baffles of each group.

Should the engine backfire and cause a back pressure in the casing 15, the valve 22 closes and the pressure unseats the door 30 and escapes to the atmosphere. The door 30 may be also manually opened to permit foreign matter accumulated within the bottom of the casing 15 to be removed.

While the invention is shown and described in connection with an automobile engine, obviously, it may be used with airplanes, boats and other engine driven vehicles.

The invention is susceptible of various changes in its form, proportions and minor details of construction and the right is herein reserved to make such changes as properly fall within the scope of the appended claim.

Having described the invention what is claimed is:—

An air cleaner comprising a casing having a pair of inlets and an outlet located in one end thereof and connected to a carburetor, one of said inlets located in the other end of the casing and the other inlet located in the side wall of said casing and in communication with the crank case of an engine, a self closing valve connected to the other inlet located at one end of the casing and in communication with the interior of an automobile body and opened by the suction of the engine and adapted to prevent back pressure from escaping into the body of the automobile when the engine back-fires, groups of arcuately curved baffles in the casing and one group intercepting the incoming air from the automobile body and directing the said air toward the bottom of the casing and the other group directing air from the bottom of the casing toward the outlet, the air and fumes entering the casing

from the crank casing of the engine being directed toward the bottom wall of the casing by the upper baffle of each group, said casing having an entrance in the bottom wall thereof with the inner ends of the baffles disposed thereover, and a self closing and outwardly swinging door for said opening and adapted to open under back pressure in the casing and to be opened manually for removing foreign substances clogged in the casing and adhering to the baffles.

In testimony whereof we affix our signatures.

RAY F. GORDON.

JAMES S. GWALTNEY.
